(57) **CLAIM**

The ornamental design for a retractable light assembly, as shown and described.

DESCRIPTION

FIG. 1 is a perspective view of the retractable light assembly showing our new design with its electric lamp assembly fully raised, taken from above and to the right-front side;

FIG. 2 is another perspective view of the retractable light assembly of FIG. 1, taken from above and to the right-rear side;

FIG. 3 is right side elevation of the retractable light assembly of FIG. 1;

FIG. 4 is a left side elevation of the retractable light assembly of FIG. 1;

FIG. 5 is a rear elevation of the retractable light assembly of FIG. 1;

FIG. 6 is a front elevation of the retractable light assembly of FIG. 1;

FIG. 7 is a top plan view of the retractable light assembly of FIG. 1;

FIG. 8 is a bottom plan view of the retractable light assembly of FIG. 1;

FIG. 9 is a perspective view of the retractable light assembly of FIG. 1, taken from above and to the right-front side, and shown mounted in a work surface with its electric lamp assembly skewed to the right-rear and rotated counterclockwise as viewed from above;

FIG. 10 is another perspective view of the retractable light assembly of FIG. 1, shown with its electric lamp assembly retracted slightly downwardly from the fully raised position of FIG. 1;

FIG. 11 is another perspective view of the retractable light assembly of FIG. 1, shown with its electric lamp assembly retracted further downwardly from the position of FIG. 10;

FIG. 12 is another perspective view of the retractable light assembly of FIG. 1, shown with its electric lamp assembly retracted nearly fully downwardly;

FIG. 13 is another perspective view of the retractable light assembly of FIG. 1, shown with its electric lamp assembly fully retracted;

FIG. 14 is a right side elevation of the retractable light assembly of FIG. 13;

FIG. 15 is a left side elevation of the retractable light assembly of FIG. 13;

FIG. 16 is a front end elevation of the retractable light assembly of FIG. 13;

FIG. 17 is a rear end elevation of the retractable light assembly of FIG. 13;

FIG. 18 is a top plan view of the retractable light assembly of FIG. 13; and,

FIG. 19 is a bottom plan view of the retractable light assembly of FIG. 13.

The broken lines are included for the purpose of illustrating portions of the retractable light assembly that form no part of the claimed design.
